UNITED STATES PATENT OFFICE.

JOHN BERGESEN, OF NEW YORK, N. Y.

STEERING-ENGINE.

1,116,975.

Specification of Letters Patent. Patented Nov. 10, 1914.

Application filed September 11, 1913. Serial No. 789,250.

To all whom it may concern:

Be it known that I, JOHN BERGESEN, a citizen of the United States, and a resident of the city of New York, borough of Brooklyn, in the county of Kings and State of New York, have invented a new and Improved Steering-Engine, of which the following is a full, clear, and exact description.

10 This invention relates to improvements in steering engines, and is designed to present an improved structure over applicant's former Patent No. 821,398, issued May 22, 1906.

15 The object of the invention is to provide a simplified structure wherein a slight movement of the valve mechanism will readily move the piston in either direction.

Another object of the invention is to 20 provide an improved valve which is simple and strong in structure, and which may be easily applied and removed.

In carrying out the object of the invention the cylinder of the engine may be of 25 any desired kind, as for instance of substantially the same kind and shape as in my former patent above mentioned. Arranged in the journal for the piston, which has an oscillating piston, is a valve designed to control the inlet and outlet from the cylinder through suitable ports in the journal or piston rod. This valve member is actuated by a suitable shaft having an engaging end which engages the valve member so that 30 whenever the shaft is turned the valve member will be correspondingly turned. Associated with the valve member is an inlet for the pressure which is designed to be adjustably positioned so that the pressure may be 35 led into the controlling valve from any desired point.

In the accompanying drawings—Figure 1 is a top plan view of an engine embodying the invention; Fig. 2 is a section through Fig. 1 approximately on line 2—2; Fig. 3 is a section through Fig. 2 approximately on line 3—3; Fig. 4 is a section through Fig. 2 approximately on line 4—4; Fig. 5 is a side elevation of the controlling valve; Fig. 6 is an end view of the controlling valve shown in Fig. 5.

Referring to the accompanying drawings by numeral 1 indicates the cylinder and 2 the piston arranged therein, piston 2 being rigidly connected to or formed integral with a bearing shaft or piston rod 3. It will be

observed that this type of engine is the oscillating type, and is designed ordinarily for steering purposes though it may be readily used in other ways. The piston in this form of engine merely oscillates or moves back and forth within the limits of the cylinder, which back and forth movement is conveyed through any suitable means to the rudder of a ship or to any other device being operated so as to give the same a back and forth movement.

The journal member or piston rod 3 is formed with a longitudinal bore 4 which is in free communication with ports 5 and 6, and the removable head or end 7. The end 7 is held in place by studs and nuts 8, and may be adjusted so that the ports 5 and 6 may extend at any desired angle, port 6 being shown closed by a plug, while port 5 is open so as to receive pressure from any suitable supply. Extending through the head 7 is a valve operating shaft 9 provided with a suitable packing 10 and formed with an end member 11 merging into an overhanging lip 12, the end member 11 fitting between the flanges or projections 13 and 14 on the valve 15 while lip 12 projects over part of the valve and thereby the valve is held properly in place, so as to continually register with the exhaust port 16. The valve 15 (Figs. 5 and 6) is formed with a passageway 17 continually in register with exhaust port 16, and designed to be brought into registry with ports 18 and 19 of cylinder 1 upon the actuation of the shaft 9. It will be noted from Figs. 1 and 4 that valve 15 does not entirely fill the bore 4 except at the extreme end so that the pressure may enter port 18 while port 19 is in registry with the exhaust port 16 and vice versa. By arranging the lip 12 as shown in Fig. 2, and by providing a shoulder 21, the valve cannot be assembled incorrectly, and also the pressure on the valve cannot move shaft 9 longitudinally.

In connection with the piston rod 3 it will be observed from Figs. 3 and 4 that two strips of packing 22 and 23 are provided, which continually contact with the piston rod 3 at all times, regardless of the movement thereof. Co-acting with these packing members are packing members 24 and 25 mounted in the piston 2 and acted on by springs 26 and 27, so as to properly divide or separate the exhaust side of the piston from the pressure side. By pro-

viding these packings 22 to 25, inclusive, no pressure or exhaust can affect the interior of the cylinder except through the valve, whereby a maximum efficiency is presented with a minimum number of parts and a simple, strong structure. It will be evident by use of the springs 26 and 27 that the packing members 24 and 25 are self adjusted, and will take up the usual wear so that 10 a tight joint is presented until the packings are entirely worn out when they may be easily renewed.

Connecting with the shaft 9 is an operating lever 20 which may be actuated by any 15 desired means but which is manually controlled for varying the position of the valve 15. At the opposite end of the engine an arm 21 is provided which is rigidly secured to the piston rod 3, and is designed to actuate a cable or other means for transmitting power to the rudder or other devices 20 being operated. In case it is desired to turn the rudder in a certain direction arm 20 is moved which will shift valve 15, for instance so as to allow pressure to enter into 25 port 18 and the exhaust to pass out port 19. This will cause the piston 2 to move to the right (Fig. 4). If the valve is moved only 30 a short distance a small quantity of the pressure will be admitted and then the piston will move and automatically shut off the pressure while simultaneously shutting off the exhaust. The piston 2 will by these 35 means be held in a new position until positively moved to another position. This ability for moving the piston to a given position and holding the same in that position is of importance as it insures the proper 40 turning of ships at any time with a minimum amount of power.

In describing the device the same has been described as being operated by pressure, which pressure may be of any desired kind, as for instance steam, oil, water, air, or 45 gas under pressure. It is also evident that the device may be used for any purpose to which it is adapted, as for instance for steering engines on vessels, air ships, vehicles and similar devices. In the drawings the 50 cylinder has been made so that the piston will have a stroke substantially 90°, but it is evident that this stroke could be greater or less as occasion might require without departing from the invention, the only 55 requisite being to make the cylinder to include more of a circle.

Having thus described my invention I claim as new and desire to secure by Letters Patent—

60 1. In an oscillating piston engine, the combination with a piston and a shaft secured thereto, said shaft being formed with a longitudinal bore having a pair of ports, of a housing for said piston, said housing surrounding part of said shaft, a valve

member loosely arranged in said bore and pressing against the end and side walls thereof, said shaft being formed with an exhaust port registering with one end of said valve, said valve being formed with an exhaust passageway designed to be brought into registry with either of said ports, means for directing steam into said bore, and a manually operated shaft for shifting said valve member. 75

2. In an oscillating piston engine, the combination with an engine cylinder piston and shaft, of a housing inclosing part of said shaft, a valve seat arranged in said shaft and dividing the shaft into live and 80 exhaust compartments, a valve co-acting with said seat for controlling the live pressure acting on said piston and the exhaust therefrom, and a manually operated shaft for moving said valve, the movement of the 85 valve being in the same direction as the movement of the piston when pressure is acting thereon.

3. In an oscillating piston engine, the combination with an engine cylinder piston and a power shaft connected therewith, of a housing inclosing part of said shaft, said shaft being formed with a longitudinal bore merging into an exhaust bore, with a pair of ports communicating with said longitudinal bore, a valve formed with a single passageway and with shouldered portions, manually operated means for actuating said valve for causing the shouldered portions to uncover said ports, and said exhaust passageway to register with said ports, said piston following said valve and covering said ports, whereby said power shaft is moved in a direct proportion to the movement of said valve. 100

4. In an oscillating piston engine, a housing, a piston arranged in said housing, a shaft connected with said piston and moved thereby, said shaft being formed with a longitudinal bore forming pressure and valve chambers, and having a pair of ports opening on opposite sides of said piston, and an exhaust passageway extending from the end of the bore, a valve member formed with an arc-shaped passageway, said arc-shaped passageway having one end continually in registry with said exhaust port, and the opposite end normally opposite said piston whereby the exhaust port is normally closed, a manually operated member connected with said valve, and means for actuating said operating member, whereby said valve may be shifted so as to cause either of said ports to register with the live pressure and either port to register with 115 said arc-shaped passageway. 120

5. In an oscillating piston engine, a housing, a piston arranged to oscillate in said housing, a shaft connected with said piston, said shaft having a longitudinal bore de- 130

fining a live pressure compartment, an exhaust bore and a pair of ports opening into the opposite sides of said piston, a valve member partially filling said bore and formed with an exhaust passageway, said valve member being formed with a shoulder for normally closing said ports, and with an exhaust passageway continually registering with the exhaust passageway in said 5 shaft and covered by said piston when said shoulders cover said port, an operating shaft connected with said valve member for turning the same, whereby one of said ports is brought into registry with said live pressure compartment, and the other of said ports is brought into registry with the exhaust passageway of the valve member.

6. In an oscillating piston engine, a housing, an oscillating piston arranged in said 10 housing, a shaft secured to said piston and operated thereby, said shaft having a longitudinal bore merging into an exhaust bore, said shaft being also provided with a pair of ports opening on opposite sides of said piston, a valve formed with an arc-shaped passageway seated on the bottom of said bore, whereby said longitudinal bore and said exhaust bore are divided, said piston being of a width sufficient to normally cover the exhaust bore, and the valve member being formed with over-hanging portions designed to cover said ports while the piston is covering the exhaust passageway, a controlling shaft connected with said valve 15 member for shifting the position thereof, and means for directing pressure into said longitudinal bore.

7. In an oscillating piston engine, a housing, an oscillating piston arranged in said 20 housing, a shaft rigidly secured to said piston formed with a longitudinal bore and an

exhaust bore, said shaft being also formed with a pair of ports opening on opposite sides of said piston, a valve formed with an exhaust passageway continually in communication with said exhaust passageway, said valve member dividing the exhaust passageway in said shaft from said longitudinal bore, said valve member being also formed with a pair of flanges, whereby a socket is 25 formed in one end, an operating member arranged with one end fitting into said socket, said end having an overlapping portion engaging the lower part of said valve, whereby the valve is held properly on its seat, the 30 pressure in the valve chamber assisting the operating member in holding the valve properly seated, and means for directing pressure to said longitudinal bore.

8. In an oscillating piston engine, a housing, an oscillating piston arranged in said 35 housing, a shaft connected with said piston and operated thereby, said shaft being formed with a longitudinal bore having an exhaust passageway and a pair of ports 40 opening on opposite sides of said passageway, a valve member arranged in said bore designed to control the inlet and exhaust, a head for said shaft formed with a pair of passageways, means for closing one of said 45 passageways, means for adjustably securing said head in position, and a valve controlling shaft extending through said head and engaging said valve.

In testimony whereof I have signed my 50 name to this specification in the presence of two subscribing witnesses.

JOHN BERGESEN.
